UNITED STATES PATENT OFFICE.

LESTER J. HILL, OF LEXINGTON, NORTH CAROLINA.

THREAD STAND.

Application filed November 2, 1923. Serial No. 672,413.

To all whom it may concern:

Be it known that I, LESTER J. HILL, a citizen of the United States, residing at Lexington, in the county of Davidson and State of North Carolina, have invented certain new and useful Improvements in a Thread Stand, of which the following is a specification.

The present invention relates to knitting machines and the like, and has particular reference to a thread stand for supporting wound bobbins for artificial silk and the like used in the manufacture of hosiery.

At the present time these bobbins are supported upon the ordinary thread stand or bracket to support bobbins that have been wound by a winding machine, and these ordinary stands are not adapted to support bobbins of artificial silk because these stands are adapted to support bobbins that have been cross wound and the silk will not feed properly from the bobbins in this type of stand. Even when artificial silk is cross wound on the bobbin it cannot be taken off satisfactorily, particularly when the silk is of inferior quality or when knots are tied in the same. A further disadvantage with the present thread stand is that when the feeding of the thread is suddenly stopped, the bobbin continues to spin sufficiently to slacken the thread and loop the same downwardly against the side of the wound bobbin, with the result that as soon as the thread is started in its feeding operation the slack is taken out of the thread and the latter is subjected not only to the sudden jar incident to the starting of the bobbin but is also caught against knots or other protruding portions of the thread which frequently results in the breakage of the thread or the dislodgement of the bobbin.

The present invention has for an object the provision of a thread stand which is adapted to overcome the above and various other objectionable features which have been found by using the common type of thread stand, and which will prevent the catching of the loop or slack of the thread upon the knots or projections on the wound bobbin, particularly below the conical upper end thereof.

Another object of the invention is to provide a stand which may receive the usual artificial silk bobbin and will permit the knitting machine to continue in its operations to use the thread without breaking

the thread or imposing irregular friction on the thread.

Another object of the invention is to provide a thread stand with an adjustable rover support and an adjustable spindle for receiving the bobbin, the spindle being adjustable relatively to the rover to maintain the bobbin and the rover in axial alignment at different adjustments. This feature of the invention accommodates bobbins of different sizes and insures the proper take off of the thread and prevents the same from becoming entangled with the knots or other projections of the bobbin.

A further object of the invention is to provide a two part stand with the parts relatively adjustable and arranged to support the eyelet or rover in one part and the spindle or bobbin carrier in the other part, the spindle being so mounted that it may be quickly swung into upright position for receiving a bobbin and for the easy removal of an empty bobbin, and also providing an adjustment for the spindle to determine its position of rest according to the adjustment of the parts of the stand. The above and various other objects and advantages of this invention will in part be described in and in part understood from the following detailed description of the present preferred embodiment, the same being illustrated in the accompanying drawings, wherein:

Fig. 1 is a side elevation of a thread stand constructed according to the present invention and showing a wound bobbin thereon and with the thread in place.

Fig. 2 is a similar view with the bobbin and thread removed and showing the spindle in raised position for receiving a bobbin.

Fig. 3 is a similar view with parts shown in section and with the portions of the thread stand extended to receive a large bobbin.

Fig. 4 is an outer end elevation of the thread stand.

Fig. 5 is a fragmentary enlarged section taken through a portion of the stand, showing the rover in section and in position, and

Fig. 6 is a detail view partly in section of the bobbin support, showing the pivot bolt for connecting the spindle to the flange.

Fig. 7 is a transverse section taken on the line 7-7 of Fig. 2 through the stand.

Referring to the drawings, 10 and 11 designate a pair of sections which are of any

suitable construction but which are adjustable relatively to each other. These sections 10 and 11 may be of strap iron or the like having overlapping bases 12 and 13 respectively and with the section 12 provided with a longitudinal slot 14 to receive therethrough a pair of machine screws 15 which are threaded in the lower base portion 13. The screws 15 form set screws and are adapted to maintain the sections 10 and 11 in true alignment at all adjustments. The section 11 is provided with suitable openings for receiving attaching screws 16 or the like for securing the thread stand to a knitting or other machine. The section 11 has a vertically extending portion at the rear end of the base 13 and which is forked at its upper end to provide spaced arms 17 between which is pivotally mounted a bobbin carrier or spindle. As shown in Fig. 6 the bobbin carrier comprises an elongated rod or spindle 18 the inner end of which has a transverse opening therethrough and is fitted in a collar 19 provided with a registering opening and also with a base flange 20 upon which the bobbin 21 is adapted to rest. The spindle 18 and sleeve 19 are coupled together by a bolt 22 which passes through the forked arms 17, and the bolt 22 has a binding nut 23 which engages the outer side of one of the arms 17 to frictionally bind the arms against the opposite sides of the sleeve or collar 19, the latter being flattened at its opposite sides to receive the arms.

This bobbin holder is adapted to be swung upwardly as shown in dotted lines in Fig. 2 to receive the bobbin and is then adapted to be swung down into an inclined position as shown in Figs. 1 and 2. A set screw 24 is threaded diagonally upward through the vertical portion of the section 11 and forms an adjustable stop for engagement with the flange 20 of the bobbin holder to support the latter at the desired inclination.

The section 10 is bent upwardly at less than a right angle as at 25 and has at its upper end a returned portion which is bent at less than right angles to the portion 25 and which terminates in spaced relation to the outer end of the spindle 18. The upper end of the section 10 carries a rover or eyelet 26 of porcelain or the like through which the thread 27 is adapted to pass.

From Fig. 1 it will be noted that the bobbin 21 and its carrier are adjusted by means of the stop 24 into substantially axial alignment with the rover 26 so that the thread 27 will normally tend to loop downwardly and at the same time will be free to swing about the bobbin 21 in the path shown by the dotted line. The bobbin 21 is shown as having the usual knots 28 below the conical section and by inclining the bobbin as shown in Fig. 1 the looped portion of the thread 27

is maintained out of contact with the knots and with the sides of the bobbin so that no undue friction or breakage of the thread can occur.

When the sections 10 and 11 are spread apart as shown in Fig. 3, the bobbin holder is correspondingly adjusted by retracting the stop 24 and permitting the spindle 18 to swing downwardly from the dotted line position into the full line position. Various adjustments of the bobbin holder may thus be made to correspond with various adjustments of the sections 10 and 11 of the thread stand.

It is of course understood that various changes and modifications may be made in the detail of construction and design of the above specifically described embodiment without departing from the spirit of this invention, the changes and modifications being restricted only by the scope of the following claims.

What is claimed is:

1. A thread stand comprising a base, a pair of spaced upright members mounted on said base for adjustment towards and away from each other, a rover mounted in one upright member, a bobbin holder pivotally mounted on the other upright member for vertical swinging movement, and a set screw threaded through the last mentioned upright member for engaging said bobbin holder and holding the bobbin holder at an upward incline towards its free end and in axial alignment with said rover. 100

2. A thread stand comprising a base, a pair of spaced upright members mounted on said base, one of said upright members being of greater length than the other member and having a portion inclined towards the same, clamping means mounted on the base and adapted to hold the upright members in spaced relation to each other, a rover mounted in the inclined portion of the longer upright member, a bobbin holder pivotally mounted on the shorter upright member and adapted to be inclined toward said first upright member, and a stop adjustably mounted in said second upright member and adapted to engage the bobbin holder to hold the same at an incline and in axial alignment with said rover. 110

3. A thread stand comprising a short upright section, a bobbin holder mounted on said upright section, a set screw threaded through said section and arranged to engage the lower portion of the bobbin holder to maintain it at the desired angle of inclination, a relatively long section arranged in spaced relation to the short section and being inclined toward the same, and a rover mounted in said long section opposite to the outer end portion of the bobbin holder. 120

4. A thread stand comprising a pair of upright members arranged in spaced apart 130

relation and with one member inclining toward and arranged higher than the other member, a bobbin support comprising a spindle for receiving a bobbin and a collar surrounding the inner end of the spindle and having a base flange to support the bobbin, a bolt extending transversely through the collar and the spindle for connecting the same together and mounted in

10 said other member for pivotally supporting the bobbin holder thereon, a rover mounted in said higher section with its axis intersecting the axis of said bolt, and an adjustable stop carried by the first section for engagement with said bobbin holder for 15 maintaining it substantially coincident with the axis of said rover.
